UNITED STATES PATENT OFFICE.

SAMUEL A. BENNER, OF PITTSBURGH, PENNSYLVANIA.

CAR PART.

1,267,498.

Specification of Letters Patent. Patented May 28, 1918.

Application filed September 15, 1913, Serial No. 789,823. Renewed October 26, 1917. Serial No. 193,744.

To all whom it may concern:

Be it known that I, SAMUEL A. BENNER, a citizen of the United States, and resident of Pittsburgh, in the county of Allegheny and State of Pennsylvania, have invented a new and useful Improvement in Car Parts; and I do hereby declare the following to be a full, clear, and exact description thereof.

My invention relates to improvements in car parts and is particularly concerned with the provision of an improved blank or section from which the desired car part may be constructed. The object of the invention is to reduce the intrinsic weight of the frame or body member of a car part to a minimum, to lower the cost of production and at the same time to provide a structure of much greater strength than has been heretofore found practicable in order that the car part may be advantageously employed in the construction of heavy tonnage cars without materially increasing the weight of the car itself. The blank or section from which the car part is to be constructed according to this invention is equally well adapted for use as the body of a truck bolster, a body bolster, truck side frame, brake beam center or side sill or end sill of a car.

In the drawings which illustrate preferred forms of the invention, Figure 1 shows one form of section from which the car part may be constructed; Figs. 2 and 3 illustrate modified forms of sections respectively; Fig. 4 is a view in side elevation indicating the manner in which the blank or section may be cut or sawed to adapt it for use in the construction of the car parts; Fig. 5 is a view in side elevation of a truck side frame exemplifying one adaptation of the invention; Fig. 6 is a longitudinal central section of the frame shown in Fig. 5; Fig. 7 is a transverse section on the line 7—7 Fig. 5; Fig. 8 is a view in side elevation indicating an adaptation of the invention for a truck bolster; Figs. 9 to 18 inclusive indicate modified forms of the blank or body section adapted for use as the body portion of the car part. Figs. 19 and 20 show further modifications.

In the embodiment of the invention illustrated in Figs. 1 and 4 to 8, inclusive, and referring first to Fig. 1, my improved form of section or blank comprises a rolled section having a comparatively thick transverse web 1 from one side of which projects a plu-

rality of flanges such as 2 and 3, and from the opposite side corresponding flanges 4 and 5. The first step in the utilization of this blank after it is rolled is to saw or otherwise cut the web 1 intermediate of its ends as between the points A and B through from side to side and longitudinally of the web, as at 6 Fig. 4, thus dividing the web into base members 7 and 8. The base member 7 thus forms with the flanges 2 and 3 a continuous channel member and the base member 8 forms with the flanges 4 and 5 at the opposite side of the web a second continuous channel member. These channel members unite at each end of the blank to form double channeled or reinforced ends for the car part.

In utilizing this blank so prepared for the construction of a truck side-frame, for example, the upper channel member 2—7—3 is bent or stretched upwardly as indicated in Fig. 5 and the lower channel member 4—8—5 is bent or stretched downwardly to form the tension member of a truck side frame. The ends of the upper flanges 2 and 3 may be conveniently sheared off as at 9, 9, and the lower flanges 4 and 5 sheared off at 10, 10, to form seats for the journal boxes 11 which may be secured to the opposite ends of the frame by the bolts 12. A suitable form of pedestal 13 may be interposed between the pressure and tension members of the frame, said pedestal having flanges 14 and 15 which may be riveted or bolted through and through to the channel member 2 and 3, and 4 and 5, respectively.

Thus it will be seen that my improved rolled blank provides an unusually efficient body structure for a truss frame of any sort, since the truss elements, such as the compression and tension members are in the form of continuous channels, each having a complete and solid base member extending continuously throughout its length. Furthermore, the base members or webs of these channel shaped truss members are united at the ends of the body, thus presenting their combined thickness and strength at their extremities, thus affording an unusually strong structure at the ends, so that when such blank is utilized as the body of a truck side frame the flanges may be cut away to any convenient extent as illustrated in Figs. 5 and 6 to afford proper seats for journal boxes, or when the blank is used for a truss

of any kind these seats present strong and convenient bases for resting the ends of such truss member.

It will be noticed particularly that the channels of which both the compression and tension members consist are formed not by shearing at right angles to the base web of the section, but by cutting or sawing this web transversely parallel to its opposite flat faces. This results in several distinct advantages; first, both compression and tension members are provided with webs extending entirely throughout their width as well as continuously throughout their length so that said members are adapted to resist not only the bending and stretching strains to which they are ordinarily subjected but also to resist lateral and twisting strains also commonly sustained in the use of a car part. Again, by leaving the thickness of the web at the opposite ends of the structure and beyond the transversely cut portion intact, these ends possess unusual strength. Furthermore, the channel portions forming the tension members are in all cases immediately below the compression member instead of being offset to one side or intermediate the sides as in the case where the web is sheared at right angles to its flat faces.

As indicated in Fig. 1 the transverse web 1 may be so cut that the base 7 of the upper or compression channel member is of greater thickness than the base member 8 of the lower or tension channel member, thus making a heavier compression member to bear the greater strains to which such member is ordinarily subjected. Also the flanges 4 and 5 may be of less thickness than the flanges 2 and 3 and may correspond in thickness to the base 8 of the lower channel. Similarly, the base 7 of the upper channel may correspond in thickness to the greater thickness of the flanges 2 and 3. The exact dimensions of the several parts will of course be determined by practical experience, but in general it may be said that the total outside width of the section may be eight inches, the flanges 2 and 3 and the base 7 of the upper channel may each be one inch in thickness, while the flanges 4 and 5 and the base 8 of the lower channel member may be substantially three quarters of an inch in thickness. It is, to be understood, however, that these dimensions are given by way of suggestion only.

In constructing a car bolster from a section of this character, as shown in Fig. 8, the blank may be sheared along the line 6 as before and between the points *a* and *b*. The ends of the blank may then be clamped in a suitable press and the lower channel or tension member of the bolster comprising the flanges 4' 5' and the base 8' may then be bent or stretched, or both bent and

stretched downwardly from the upper channel member comprising the upper flanges 3', 4' and the channel base 7'. The compression and tension members may then be secured together and reinforced by means of rolled, pressed or cast strut members such as I-beams 15. This form of bolster has the particular advantage that the channel bases 7' 8' may be bored at 16 and 17 respectively to receive the king-bolt, thus affording ample lateral support for said bolt.

Of the modified forms of the section from which the desired structure may be produced, that in Fig. 2 comprises the thick web 18, the edge flanges 19 and 20 and the opposite flanges 21 and 22 which are preferably inset from the side edges of the blank, and if desired the inner faces such as 23 of the upper flanges may be parallel and in the same plane as the outer faces, as 24, of the lower flanges. In this case the web may be sheared longitudinally and intermediate of its ends along a line within the thickness of the web indicated at 25.

In Fig. 3 the section resembles that shown in Fig. 1, except that the flanges 26, 27 may be of the same thickness as the flanges 28 and 29, and a thickened web may be cut or sawed along the line 30.

In Fig. 9 the blank comprises a transverse web 31 having laterally projecting portions 32 and 33, extending beyond the flanges 33, 33 on one side of the web and the flanges 34, 34 on the opposite side. The extensions 32 of the web afford a breadth of base for the pedestal of a side frame or for any other purpose where such broad base is required to reinforce the structure against lateral thrust.

In the form shown in Fig. 10 the blank may comprise the thickened web 35 and the series of flanges, here four in number, 36, 36, 36, 36, whereas the flanges 37, 37, on the opposite side may be two in number and may be positioned in alignment with the intermediate flanges 36 on the upper side, respectively. The web may be sheared along the line 38, thus affording a broad web 39 for the base of the tension member equal in width to the broad web 40 of the compression member.

In Fig. 11 the blank comprises a thickened web 41 and a plurality of flanges 42 and a corresponding number of flanges 43 projecting from the opposite side of the web and as here shown, in alignment respectively with the flanges 42. The transverse web may be sheared along the line 44 to form the bases, respectively, of the upper and lower channel members.

Fig. 12 resembles the structure of Fig. 9 except that the flanges 45 on one side may be greater in thickness than the flanges 45 on the opposite side of the web 47 and the

web may be cut along the line 48 forming a base 49 for the tension member of substantially the same thickness as the flanges 46 and a base 50 for the compression member of substantially the same thickness as the flanges 45 thereof.

The form shown in Fig. 13 comprises a combination of that shown in Figs. 2 and 9, respectively, in that the web 51 has not only the flanges 52 at one side and the flanges 53 at the other, but also the lateral extensions 54. Likewise the web has the greater thickness between the flanges 53 so that when sheared along the line 55 the upper channel is provided with a base 56 prolonged into the extension 56' and the lower channel is provided with the base 57.

In Fig. 14 the blank comprises a combination of the forms shown in Figs. 2 and 10, in which the web 58 has a series of flanges 59 on one side and a pair of flanges 60 on the opposite side, the web being thickened at 61 to supply the base for the lower channel member when the web is sawed along the line 62.

In Fig. 15 is illustrated a form of blank peculiarly adapted for use in a truck bolster in which the thickened web 63 is provided with the upstanding flanges 64 of somewhat more than usual width, which in the construction of the bolster may, if desired, be bent inwardly or outwardly at 65 to form the compression member in the form of a partially closed member or a laterally strengthened member, and thus also affording a base or rest for the body or other corresponding bolster. This blank is also provided with the opposite flanges 66 and the thickened portion of the web 67 forming the base of the lower channel or tension member.

In Fig. 16 the blank comprises the web 68 having a plurality of flanges 69 on one side arranged in pairs, and opposite each pair of said flanges are the flanges 70. The web is thickened at 71 and 72 to be sheared along the line 73 to form the complete lower channel members opposite the channel members formed by the pairs of flanges 69, respectively, while the central portion 73 of the web forms a complete transverse base for the upper or compression member.

In Fig. 17 the blank consists of the web 74, the flange 75 on one side and the flange 76 on the opposite side. This web may be severed along the line 77 forming truss members having transverse bases and these upstanding reinforcing flanges.

In Fig. 18 the blank comprises the base 78, the pair of flanges 79 and the flange from the opposite side 80. This blank may be severed along the line 81 to form a truss construction having one truss member in the shape of a channel member and the other 65 having a transverse base and a flange 80.

In Fig. 19 the blank comprises the web 82 having a flange 83 on one side and a reinforcing member 84 on the opposite side. The web is severed along line 85.

In Fig. 20 the blank comprises the web 86 and the reinforcing member or flange 87 on one side and the reinforcing member 88 on the opposite side. This web likewise is severed along the line 89.

The form shown in Figs. 18, 19 and 20, inclusive, are particularly well adapted for use in brake beam constructions in which when the web is severed, the portion of the blank on one side of the cut may remain straight, while the one on the opposite side may be bent or stretched to form a truss member, reinforcing the straight member.

While in most instances the word flange has been used to designate the reinforcing ridges or ribs, on opposite sides of the web, it is to be understood that this term is not necessarily limited strictly to straight flanges, such as shown in the majority of figures, but may also apply to reinforcing ribs or members of varied shapes such for example as illustrated at 84 and 88 in Figs. 19 and 20.

While I have herein shown and described several modifications of the invention it is to be understood that the same may be modified in structure and relative arrangement of parts within the scope of the appended claims.

What I claim is:

1. A blank for a car part or other structure consisting of a rolled section comprising a web having one or more flanges projecting from the opposite faces thereof, said web being cut or sawed intermediate its ends in a plane substantially parallel with its opposite flat faces, whereby the parts on the opposite sides of said cut may be bent or stretched to form continuous truss members.

2. A blank for a car part or other structure consisting of a rolled section comprising a web having one or more flanges projecting from the opposite faces thereof, said web being cut or sawed intermediate its ends in a plane substantially parallel with its opposite flat faces, whereby the parts on the opposite sides of said cut may be bent or stretched to form continuous truss members, the web and flange being of varied thickness.

3. A blank for a car part or other structure consisting of a rolled section, comprising a web having a plurality of flanges projecting from the opposite faces thereof, said web being cut or sawed intermediate its ends in a plane substantially parallel with its opposite flat faces whereby the parts on the opposite sides of said cut may be bent or stretched to form continuous channel shaped truss members.

4. A blank for a car part or other structure consisting of a rolled section, comprising a web having a plurality of flanges projecting from the opposite faces thereof, said flanges on each side being arranged in pairs and said web being cut or sawed in a plane substantially parallel with its opposite faces whereby said sheared portions may be expanded to form truss members, said pairs of flanges each forming with the sheared portions of the web, respectively, continuous channel members.

5. A blank for a truss member comprising a rolled section having a transverse web, a plurality of flanges projecting from opposite sides thereof, said flanges on each side being arranged in pairs respectively, the pairs of flanges on one side being directly opposite the pairs of flanges on the opposite side, respectively, said web being cut or sawed intermediate its ends on a plane substantially parallel with its opposite flat faces and said cut portions being adapted to be expanded to form continuous channel shaped truss members directly opposite each other.

6. A blank for a car part or other structure consisting of a rolled section, comprising a web having a plurality of flanges projecting from the opposite faces thereof, said web being cut or sawed intermediate its ends in a plane substantially parallel with its opposite flat faces whereby the parts on the opposite faces of said cut may be bent or stretched to form continuous channel shaped truss members, the outer edges of said web extending beyond the outer flanges.

7. A blank for a car part or other structure consisting of a rolled section, comprising a web having a plurality of flanges extending from one side thereof and a plurality of flanges extending from the opposite side and offset from the first named flanges, said web being cut intermediate its ends in a plane substantially parallel with its opposite flat faces whereby the sheared portions of the web and said flanges may constitute continuous channel shaped truss members.

8. A blank for a car part or other structure consisting of a rolled section, comprising a web, a plurality of flanges extending from one side of said web, said web being thickened for a portion of its width, a plurality of flanges extending opposite the first named flanges from said thickened portion, said web being cut or sawed intermediate its ends in the plane of junction of the thickened portion with the thinner portion of the web whereby said cut portions of the web may be expanded to form with said flanges continuous channel shaped truss members.

9. In a blank for a car part or other structure consisting of a rolled section, com-

prising a web, a plurality of flanges extending from one side of said web, said web being thickened for a portion of its width, a plurality of flanges extending opposite the first named flanges from said thickened portion, said web being cut or sawed intermediate its ends in the plane of junction of the thickened portion with the thinner portion of the web whereby said cut portions of the web may be expanded to form with said flanges continuous channel shaped truss members, said web being extended at its opposite sides beyond the outermost flanges to form a broadened base for one of said truss members.

10. A blank for a car or other structure consisting of a rolled section, having a web thickened throughout portions of its width, a plurality of flanges extending from one face of said web, flanges extending from said thickened portions on the opposite side of said web, said web being cut or sawed intermediate its ends in the plane of junction of said thickened portions with the thinner portion of the web, said cut portions being adapted to be expanded to form with the adjacent flanges oppositely disposed continuous channel shaped truss members.

11. A blank for a car part or other structure consisting of a rolled section, having a web, a plurality of flanges extending from one face thereof, and a plurality of flanges extending from the opposite face thereof and of less thickness than the first named flanges, said web being cut or sawed intermediate its ends in a plane substantially parallel with the opposite flat faces thereof and at a distance from the faces such that the web and flange on one side are of different thickness from that of the web and flange on the opposite side, said cut portions being adapted to be expanded to form oppositely disposed continuous channel shaped truss members.

12. A blank for a car part or other structure consisting of a rolled section, having a web, a plurality of flanges projecting from one face thereof, a plurality of flanges projecting from the opposite face thereof, each of the first named flanges being thicker than the second named flanges, said web being cut or sawed intermediate its ends in a plane substantially parallel with its opposite flat faces, at a distance from said faces to form separate webs equal in thickness to that of the flanges projecting from the adjacent faces, respectively.

13. A blank for a car part or other structure consisting of a rolled section, having a web, a pair of flanges projecting from one face thereof, a pair of flanges projecting from the opposite face thereof, the first named flanges being greater in depth than the second named flanges, said web being cut or sawed intermediate its ends in a plane

parallel with its opposite flat faces whereby said cut portions may be expanded to form oppositely disposed continuous channel shaped truss members, said deeper flanges 5 being turned inwardly to form a lateral strengthening member to partially close the channel formed of said deeper flanges.

14. A blank for a car part or other structure consisting of a rolled section, having a 10 web, a pair of flanges projecting from one face thereof, a pair of flanges projecting from the opposite face thereof, the first named flanges being of greater depth than the second named flanges, said web being 15 cut or sawed intermediate its ends in a plane parallel with its opposite flat faces whereby said cut portions may be expanded to form oppositely disposed continuous channel shaped truss members, said deeper flanges 20 being turned over to form a laterally strengthening member.

15. A blank for a car part or other structure, consisting of a rolled section compris-

ing a web having one or more longitudinal strengthening members projecting from the opposite faces thereof, said web being cut or sawed intermediate its ends in a plane substantially parallel with its opposite flat faces whereby the parts on the opposite sides of said cut may be bent or stretched to form 30 continuous truss members.

16. A blank for a car part or other structure consisting of a rolled section comprising a web and one or more flanges, said web being cut by a single cut intermediate its 35 ends in a plane substantially parallel with its opposite flat faces, whereby the parts on the opposite sides of said cut may be bent or stretched to form continuous truss members.

In testimony whereof I, the said SAMUEL A. BENNER, have hereunto set my hand.

SAMUEL A. BENNER.
